UNITED STATES PATENT OFFICE.

STANLEY J. PUKROPP, OF STURGEON LAKE, MINNESOTA.

WIRE-TAPPER.

1,100,614.

Specification of Letters Patent. Patented June 16, 1914.

Application filed August 30, 1913. Serial No. 787,445.

To all whom it may concern:

Be it known that I, STANLEY J. PUKROPP, a citizen of the United States, residing at Sturgeon Lake, in the county of Pine and State of Minnesota, have invented certain new and useful Improvements in Wire-Tappers; and I do hereby declare the following to be a full, clear, and exact description of the invention, such as will enable others skilled in the art to which it appertains to make and use the same.

My invention has for its object to provide an improved wire tapper and, to this end, it consists of the novel devices and combinations of devices hereinafter described and defined in the claims.

In the accompanying drawings, which illustrate the invention, like characters indicate like parts throughout the several views.

Referring to the drawings: Figure 1 is a view in side elevation showing a telephone mounted in an automobile and connected with the line wires; Fig. 2 is a view in side elevation of the improved telephone connections; Fig. 3 is a detail view of the contact grapples, on an enlarged scale, with some parts sectioned on the line α , α' of Fig. 2; Fig. 4 is a detail view partly in vertical section and partly in side elevation, on an enlarged scale, showing one of the joints between the several sections of the grapple rod; Figs. 5 and 6 are end elevations of the grapple rod sections shown in Fig. 4; and Fig. 7 is a diagrammatic view of the wiring of the instrument and lamp circuits.

The numeral 1 indicates, as an entirety, an automobile and the numeral 2 indicates a telephone pole having secured to its upper end the customary cross arms 3 which are provided with insulating caps 4, to each of which is secured a line wire 5. To the inner vertical face of the dash board of the automobile 1 is attached a box 6 containing a battery 7.

The numeral 8 indicates a receiving and transmitting instrument, and the numeral 9 indicates the two wires of the instrument battery circuit. The wires of this instrument circuit are attached one to each of a pair of upwardly diverging contact grapples 10 having, on their outer edges, a plurality of longitudinally spaced hooks 11, for engagement with the line wires 5. At their lower ends, the contact grapples 10 are pivotally secured, for independent movement toward and from each other, on a pin 12

anchored, at its ends, in a socket 13 secured to the upper end of a long rod 14 affording a handle for said grapples. The contact grapples 10 are insulated one from the other and from the pin 12 by a bushing 15 of suitable insulating material. The rod 14 is made up of a plurality of sections detachably connected by couplings 16 of substantially the same construction as an ordinary hose coupling. The couplings 16 comprise internally threaded sleeves 17 telescoped onto the lower ends of the rod sections with freedom for rotation thereon but held against removal therefrom by laterally projecting lugs 18. These sleeves 17 have screw threaded engagement with externally threaded collars 19 integrally formed on the upper ends of the sections of the rod 14. Disks 20 of insulating material close the ends of the rod sections.

The instrument circuit wires 9 are longitudinally extended through the rod 14 and are severed and detachably connected, at each joint thereof, by separable contacts 21 and 22. The contacts 21 are in the form of depending fingers secured to the disks 20 in the lower ends of the rod sections and arranged to enter sockets 23 formed in the disk 20 of the upper ends of the rod sections, for engagement with the contacts 22, which are in the form of flat springs. Obviously, the contact fingers 21 keep the rod sections properly aligned and held against rotation with respect to each other.

To enable the operator to attach the contact grapples 10 to the line wires 5 at night, an electric lamp 24 is mounted on a lamp bracket 25 secured to the upper end of the rod 14 in the vicinity of said contact grapples. A lamp battery circuit 26 extends from the battery 7, through the several sections of the rod 14, to the lamp 24. At each coupling 16, the wires 26 are severed and connected to spring contacts 27 secured to the insulating disks 20. Cooperating pairs of contacts 27 are properly aligned with each other by the contact fingers 21 and sockets 23. The instrument and light circuit wires are all properly insulated and, from the battery box 6 to the lower end of the rod 14, they are in the form of a single cable. In the light battery circuit 26 is a normally open switch 28 mounted on the lower end portion of the rod 14.

By means of the handle or rod 14, the contact grapples 10 may be applied to any one

pair of the line wires 5. The hook equipped upwardly diverging grapples 10 permit the device to be attached to line wires set various distances apart and also to wires that 5 extend in the same horizontal plane or wires located one above the other. The depending handle or rod 14 holds the grapples 10 in proper contact with the line wires 5. When the device is not in use, the contact 10 grapples 10 may be folded together and the several sections of the rod 14 may be separated and placed within the automobile in a compact space. In the operation of the device, two or more rod sections may be used, 15 depending on the height of the line wires 5 above the ground. At night, by operating the switch 28 to close the lamp circuit, the lamp 24 may be lighted, to illuminate the grapples 10 so that the operator may readily 20 apply the same to the line wires.

From the foregoing description, it is evident that, by the use of the improved device, telephone connections may be made anywhere along the line wires. In case the connections are not long enough to reach from 25 the automobile to the line wires, the entire device may be removed from the automobile and carried to the line wires.

What I claim is:

30 1. A line tapper comprising a rod having a contact grapple for engagement with a line circuit, wire connections leading to said grapple, and a lamp supported on said pole in the vicinity of said grapple.

35 2. A wire tapper comprising a battery, a receiving and transmitting instrument, a rod having contact grapples for engagement with the line wires, instrument wires connecting said grapples with said battery, an 40 electric lamp supported by said rod in the vicinity of said grapples, and lamp circuit wires connecting said lamp to said battery.

45 3. A wire tapper comprising a battery, a receiving and transmitting instrument, a rod made up of jointed sections, contact grapples at one end of said rod, for engagement with the line wires, and instrument wires extending through said rod and connecting said grapples with said battery, said 50 instrument wires having separable contacts at the joints of said rod.

55 4. A wire tapper comprising a battery, a receiving and transmitting instrument, a rod made up of jointed sections, contact grapples at one end of said rod for engagement with

the line wires, instrument wires extending through said rod and connecting said grapples with said battery, an electric lamp supported by said rod in the vicinity of said grapples, and lamp circuit wires extending 60 through said rod and connecting said lamp with said battery, said instrument and lamp circuit wires having separable contacts at the joints of said rod.

5. A wire tapper comprising a battery, a receiving and transmitting instrument, a rod having, at one end, folding contact grapples for engagement with the line wires, and instrument wires connecting said grapples with said battery. 70

6. A wire tapper comprising a battery, a receiving and transmitting instrument, a rod, a pair of diverging contact grapples attached to one end of said rod and having longitudinally spaced hooks for engagement 75 with the line wires, and instrument wires connecting said grapples with said battery.

7. A wire tapper comprising a battery, a receiving and transmitting instrument, a rod made up of jointed sections, a pair of folding diverging contact grapples attached to one end of said rod and having longitudinally spaced hooks for engagement with the line wires, and instrument wires extending 80 through said rod and connecting said grapples with said battery, said instrument wires having separable contacts at the joints of said rod.

8. A wire tapper comprising a battery, a receiving and transmitting instrument, a rod 90 made up of jointed sections, a pair of folding diverging contact grapples attached to one end of said rod and having longitudinally spaced hooks for engagement with the line wires, instrument wires extending 95 through said rod and connecting said grapples with said battery, an electric lamp supported by said rod in the vicinity of said grapples, lamp circuit wires extending through said rod and connecting said lamp 100 with said battery, said instrument and lamp circuit wires having separable contacts at the joints of said rod, and a normally open switch in said lamp circuit.

In testimony whereof I affix my signature 105 in presence of two witnesses.

STANLEY J. PUKROPP.
